GLUING-MACHINE.

1,166,004.

Specification of Letters Patent. Patented Dec. 28, 1915.

Application filed June 19, 1914. Serial No. 246,092.

To all whom it may concern:

Be it known that we, JAMES D. REIFSNYDER and HARRY B. SMITH, citizens of the United States, residing at Philadelphia, 5 State of Pennsylvania, and in Brooklyn, county of Kings, and State of New York, have invented new and useful Improvements in Gluing-Machines, of which the following is a specification.

10 This invention relates to a machine for applying an adhesive or glue to one side only of blanks or individual sheets.

The invention is closely related to the invention disclosed in Patent Number 726,473, 15 granted to P. S. Smith. In that patent, the construction consisted essentially of two spaced rollers having separated glue applying faces arranged in parallel relation and with the faces out of line so that the first 20 roller which touched the blank applied the glue to it in stripes or zones, and the second roller also applying the glue, in the spaces between these bands or zones, the result being that the face of the blank was completely covered with glue. Above the glue 25 applying rollers there was provided a pair of presser rollers, the axles of which were mounted in sockets so that the rollers could rise or fall with respect to a horizontal line.

30 In using this machine, the operator held a pack of the blanks in her hands and fed the pack at once through the machine, the pack being sufficiently thick to raise the presser rollers in their sockets and the weight of 35 the pack and the weight of the presser rollers pressed the lowermost blank onto the glue applying rollers. As the pack passed out from the other side of the machine, the operator segregated the bottom blank to

40 which the glue had been applied and then repeated the operation just described. In other words, a pack of the blanks was passed successively through the machine in the form of a pack. The presser rollers, of course, 45 did not come in contact with the glue applying rollers, so that they remained clean and did not operate to smear any glue accidentally on the upper face of a pack. A machine such as that just described, while it 50 is useful with the mode of operation just described, necessitates constant labor and attention on the part of the operator. Furthermore, a machine with presser rollers

of this kind cannot be used to apply an adhesive to one side only of a single blank fed 55 through the machine, because, it would be impossible to bring about the pressure on the upper surface of the blank to maintain it in contact with the glue applying rollers, for it is evident that the blank being of pa- 60 per, is very thin, and if the presser rollers would operate with a single blank, they would necessarily have glue smeared accidentally upon them from the glue applying rollers at times when there was no blank 65 passing through the machine.

A principal object of the present invention is to provide a machine which will perform the functions of the machine referred to above, but without necessitating the passing 70 of the pack of blanks through the machine, and having a construction enabling the machine to operate effectively with automatic feeding mechanism which feeds the blanks one at a time through the machine. 75 One of the difficulties of accomplishing this object is to insure that a good contact may be maintained between the blank and the glue applying faces as the blank passes through the machine. 80

One of the objects of this invention is to overcome this difficulty, and furthermore to insure that in passing through the machine the blank will have the glue applied to it throughout its entire area and particularly 85 at the tail edge, or following edge of the blank as it passes through the machine.

Another object of the invention is to arrange for guiding blanks in such a way as to prevent the smearing of glue on the 90 guides.

Further objects of the invention will appear more clearly hereinafter.

In the drawing which fully illustrates the preferred movement of our invention, Fig. 95 1 is a side elevation of a machine constructed in accordance with our invention. Fig. 2 is a plan, certain parts being shown in cross section and broken away. Fig. 3 is a front elevation of the machine, certain 100 parts being broken away. Fig. 4 is a vertical section through the machine, certain parts being broken away. Fig. 5 is a vertical section, but on an enlarged scale, particularly illustrating the feeding mechanism. 105 Referring more particularly to the parts,

10 represents the frame of the machine which may be of any suitable construction and arranged to support a tank 11 having mucilage or liquid glue. Arranged so as to pick up the glue from the glue bath 12, in this tank, we provide a wallower or roller 13 the lower part of which is immersed in the glue. Above the glue tank 11 side frames 14 are provided which afford means for supporting the principal part of the mechanism including a pair of glue applying rollers 14 and 15 which are rigidly secured to shafts 16 and 17, said shafts having rigid gear wheels 18 and 19 on their extremities which mesh with the gear wheel 20 rigid on the shaft 21 of a distributing roller 22, the face of which is in contact with the wallower 13 below and in contact above with the glue applying rollers 14 and 15. The preferred arrangement is most clearly illustrated in Fig. 4. The rollers 14 and 15 are formed with separated glue applying faces 23, and this effect is most conveniently produced by forming the glue applying faces on a series 25 of collars 24 on the rollers. As illustrated most clearly in Fig. 2, the glue applying faces of the collars are out of alignment with each other.

Arrangement is provided for guiding the blanks one by one across the upper sides of the rollers 14 and 15. In order to accomplish this, we prefer to provide feed rollers comprising an upper feed roller 25 and a lower feed roller 26, the lower feed roller being preferably formed with collars 27 which touch the under surface of the roller 25. We provide means for guiding the blank as it passes from these feed rollers so that it is guided in a direction intersecting the periphery of the first roller 15 in order to effect a good contact between the blanks and the glue applying faces of this roller, and we cause the blank to engage and adhere to the glue on a substantial portion of the periphery of the roller so that the blank adheres to, and is advanced by the glue applying roller itself and without any other roller pressing the blank upon it. In order to accomplish this, we provide guiding means between the feed rollers and the roller 15, preferably comprising a lower guide bar 28 which is disposed parallel to the rollers and provided with a plurality of strips or fingers 29 which project at right angles to the bar, one extremity of these strips being disposed between the rollers 27 of the roller 26, and the other extremity being disposed between the collars 24 of the roller 15, that is between the glue applying faces of this roller. The upper edges of these fingers are on a line which intersects the outline of the periphery, as indicated in Fig. 4, so that they tend to guide the blank in a direction intersecting the periphery of the roller.

We provide guiding means on the upper

side which preferably comprises a guide bar 30 which is substantially parallel with the guide bar 28, and this guide bar has a plurality of strips or fingers 31 which are arranged in a staggered relation in respect to the fingers 29; however, they are disposed parallel with the fingers 29 and their rear extensions 32 preferably terminate very near the glue applying face of the roller and near the plane of the upper edges of the fingers 29. These extensions 32 are preferably rounded on their ends, as shown in Fig. 4. The guide fingers 31 evidently form a guide for the side of the blank which is remote from the glue applying rollers, and the blank has a sliding engagement with these fingers as it passes onto the roller 15.

Between the rollers 14 and 15 we provide guiding means having the same general functions as the guiding means which includes bars 28 and 30; this guiding means is preferably entirely supported between the rollers 14 and 15 and preferably comprises an upper guide bar 33 which is disposed parallel with the rollers 14 and 15, and is preferably suspended from an upper bar 34 by means of adjustable bolts 35. On the under side of this upper guide bar 33 we provide a plurality of fingers 36 which are preferably thin and flat like the fingers described above, and these fingers extend at right angles to the bar. These fingers are arranged in line with the glue applying faces of the rear or second roller 14, and the lower edges of these guide fingers incline downwardly slightly, so that when the blank slides along on their edges it is guided in a direction intersecting the periphery of the roller 14. Coöoperating with the upper bar 33 we prefer to provide the lower bar 37, which is opposite to the bar 33, with fingers 38 which have a function similar to that of the fingers 29, that is, they guide the blank on its under side, the forward extensions of the fingers 38 terminating between the glue applying faces of the roller 15, and their rear extensions being disposed in alignment with and terminating adjacent to the glue applying faces of the rear roller 14. This lower bar 37 constitutes means for entirely supporting the fingers 38 between the rollers 14 and 15. One of the advantages of supporting these guides entirely between the rollers 14 and 15 is that they can be made of a more substantial construction and they can be more readily removed. Also they can be more readily adapted to the desired guiding direction at any particular point. As it may be necessary to change or adjust the guide fingers 36, we prefer to secure the bar 34 so that it can be readily removed; for this purpose, we prefer to provide slots 34^a in the ends of this bar to receive bolts having wing nuts 34^b. By loosening the wing nuts 34^b, the bar 34 can be readily removed.

The fingers 36 are preferably slightly rounded at their forward edges, and it will be observed also, that the space between the fingers 36 and the fingers 38 preferably contracts slightly toward the rear.

Behind the rear roller 14 we provide another guiding means for taking the blank off the roller 14 in order to direct it onto a conveyer, which conveyer is preferably in the form of endless belts 39 passing over rollers 40 and 41 which support the belts in an inclined position. The belts 39 are preferably disposed intermediate of horizontal belts 42 which pass around the roller 41, and which receive the blank from the conveyer 39.

The guiding means for guiding the glued blank up onto the conveyer 39 will now be described. This guiding means preferably comprises a cross bar 43 behind the roller 14 and near the upper portion thereof, and this bar is preferably provided with a plurality of fingers 44 which project substantially horizontally into the space between the glue applying faces of the roller. These fingers are preferably formed integral with upwardly curved arms 45, and they terminate over the roller 14. Hence they are supported entirely from the rear and do not interfere with the guides that are between rollers 14 and 15. The fingers 44 act as strippers to take the blank off the roller, and the forward edge of the blank is then bent upwardly by the curved arms 45 so as to turn over the blank and deposit it upon the conveyer in an inverted position, that is with the glued side uppermost. The course of the blank in passing over the rollers is indicated by the dotted line 46.

The feed rollers 25 and 26 are preferably driven in opposite directions and at the same speed by means of gear wheels 47 and 48 which are rigid on these rollers. The gear 48 which is carried by the roller 26 is driven by an idle gear 49 from the aforesaid gear wheel 19, see Fig. 1.

The rollers 41 are preferably supported on a suitable bracket 50 on the side frames 14^a.

The feed mechanism and the arrangement for operating the same will now be described. This mechanism preferably comprises a feed table 51 which may be mounted on the forward face of the tank, as shown in Fig. 4, and this feed table has a slot 52 for guiding and clamping a guide bracket 53. This guide bracket carries an adjusting bolt 54 for clamping it in any desired position so that it can assist in holding in place a pack or supply of blanks 55. The feed table 51 is preferably formed with a bracket 56 which supports a vertical feed screw 57, and on this feed screw is a threaded nut 58 which is formed as a rigid lug on a vertically movable feed shelf 59. This feed shelf supports the blanks 55 in a horizontal position

and is provided with a slot 60 through which the upper portion of the guide 53 extends.

The upper portions of the side frames 14^a are formed with guideways 61 which guide 70 blocks 62, said blocks carrying between them a horizontal feed bar 63. Near its middle point, this bar is provided with short arms 64 carrying feed rollers 65, said feed rollers having ratchet wheels 66 rigid therewith. Pivoted on each arm 64 near the feed roller is a detent 67 having a tooth 68 which is adapted to engage with the teeth of the ratchet at certain times to prevent the rotation of the feed roller. The feed rollers have rubbing faces of rubber or similar material adapted to frictionally engage the uppermost blank. In order to reciprocate the feed bar 63, which carries the rollers and reciprocates them, we prefer to provide a pair of disk cranks 69 which are connected by connecting rods 70 with arms 71 which are rigid with the feed bar 63. The arms 64 project inwardly so that when tension is being exerted in the rods 70 a slight amount of pressure is developed forcing the feed rollers down on the uppermost blanks. In addition to this, the pull on the rods, of course, produces a movement of the feed bar toward the rollers 25 and 26. When the detent 67 is out of engagement with the teeth of the ratchet wheels 66, of course, these ratchet wheels rotate freely and do not advance a blank, but we provide an arrangement such that on each rearward movement, that is on each movement toward the feed rollers 25 and 26, the rotation of the rollers will cease at a certain point so that they will then grip the uppermost blank and advance it, for this purpose, we provide a fixed feed shelf 72, see Fig. 2, and this feed shelf has two parallel channels or gutters 73 which lie directly under the detents on the rearward or feeding movement of the feed bar 63; as soon as the extremities 74 of the detents 67 pass beyond the rearmost edge 75 of the uppermost blank, they fall down onto the channels 73 so that the tooth 68 of each detent engages its corresponding ratchet wheel and stops the rotation of the roller. In this way, the detent performs the function of stopping the rotation of the feed rollers at a predetermined distance from the rearward edge of the uppermost blank.

In the operation of the feed rollers, the uppermost blanks have a tendency to arrange themselves in a more or less overlapping condition at their rear edges, and in order to increase the friction resistance on their under sides so that the uppermost blank only will be fed forward, we prefer to provide the upper face of the feed shelf 72 with pads 76 of rubber or similar material. These pads assist in preventing the for- 130

ward feeding of more than one blank at a time.

The disk cranks 69 are most conveniently driven by means of the aforesaid gear wheel 5 47 which meshes with the gear wheel 77, Fig. 1, rigid on the shaft 78 which connects the two disk cranks, which shaft is rotatably mounted in the aforesaid brackets 50. On the outward or return movement of the feed 10 bar 63, the rollers 65 are raised off of the blanks 55 until the arms 71 come against adjustable stops 79 mounted on the slide blocks 62; as soon as the arms 71 come against these stops, the blocks slide outwardly in the guideways 61.

Any suitable arrangement is provided for automatically feeding the blanks 55 upwardly so as to maintain a substantially uniform level for the uppermost blank; for this 20 purpose, the aforesaid feed screw 57 may be actuated by means of a ratchet wheel 80 rigid with the feed screw and adapted to be operated by a spring pressed pawl 81 carried on a loose arm 82 on the feed screw. 25 This arm 82 is rocked backward and forward at each rotation of the distributing roller 22 by means of a cam 83 which rotates with the roller and which actuates a rocking lever 84, said rocking lever 84 being connected by a suitable link 85 with the aforesaid arm 82. From this arrangement, it will be seen that at each rotation of the roller 22 the feed screw 67 will have a slight rotation operating to raise the nut 58 carrying 30 with it the feed shelf 59.

Any suitable arrangement is provided for regulating the amount of feed movement, so that if it becomes too great it will desist temporarily. For this purpose, we prefer 40 to provide an arrangement for throwing the pawl 81 out of operation automatically. This is preferably accomplished by means of a guard fin 86 which is formed on a loose arm 87 mounted on the lower extremity 45 of the feed screw. This arm is connected by a link 88 and a bell crank lever 89 with a shoe 90 pivotally carried on the horizontal arm 91 of the bell crank lever, and this shoe rests on the uppermost blank. If the pile 50 of blanks are fed up too high, the shoe 90 will raise the arm 91, and this rotates the trip arm 87 toward the pawl and moves the guard 86 under the pawl so as to prevent its engagement with the ratchet wheel 80, 55 or else limit the amount of its effective engagement with the ratchet.

It is understood that the embodiment of the invention described above is only one of the embodiments, or forms that the invention may take, and we do not wish to be limited in the practice of the invention, nor in our claims to the particular embodiment set forth.

A hand wheel 21^a is provided on the shaft 65 21 for rotating by hand when desired, but

the machine is normally driven by power through a pulley 20^b and clutch 20^c.

What we claim is:

1. In a machine for applying glue to individual blanks, in combination, a roller 70 having separated glue applying faces, fixed guiding means having a guiding face for engaging the face of the blank remote from the roller for guiding the blank against the said faces of said roller, said guiding face lying 75 on a line intersecting the periphery of said roller and thereby causing the blank to engage and adhere to the glue applying faces of the roller by the adhesion of the glue throughout a portion of the periphery of 80 the roller, said faces operating to advance the blank therewith, a second roller opposite said first roller and having a plurality of separated glue applying faces out of alignment with said first faces for applying 85 the glue between the points of application of the glue by said first named glue applying faces, and means adjacent the periphery of the first named roller for disengaging the blank therefrom and for guiding the 90 same onto the said second named roller.

2. In a machine for applying glue to individual blanks, in combination, a roller having separated glue applying faces, fixed guiding means including a plurality of guide fingers for engaging the face of the blank remote from the roller for guiding the blank against the said faces of said roller, said guiding fingers lying on a line intersecting the periphery of said roller and thereby 95 causing the blank to engage and adhere to the glue applying faces of the roller by the adhesion of the glue throughout a portion of the periphery of the roller, a second roller opposite said first roller and having a plurality of separated glue applying faces out of alignment with said first faces for applying 100 the glue between the points of application of the glue by said first named glue applying faces, and means adjacent the periphery of the first named roller for disengaging the blank therefrom and for guiding the same onto the said second roller.

3. In a machine for applying glue to individual blanks, in combination, a pair of 115 spaced rollers each having separated glue applying faces, the faces of one roller being out of alignment with the faces of the other roller, fixed guiding means arranged adjacent said rollers for engaging the side of 120 the blank remote from said rollers and along the surface of which the blank slides, said guiding means having a guiding face engaging the blank and extending in a line intersecting the periphery of the rollers and causing the blank to engage and maintain contact with said glue applying faces on a portion of the periphery of the rollers.

4. In a machine for gluing one side of a blank, in combination, a roller having a plu 125

- rality of separated glue applying faces, a second roller having a plurality of separated glue applying faces out of alinement with said first faces, means for guiding a blank 5 across said rollers so as to be striped with glue by said glue applying faces, a conveyer for the glued blanks disposed over said rollers and separated guide strips projecting into the spaces between the glue applying 10 faces of said second named roller, terminating over said second roller, and operating to turn over the blanks and deliver them to said conveyer with the uncoated face toward the conveyer.
- 15 5. In a machine for applying glue to individual blanks, in combination, a roller having separated glue applying faces, fixed guiding means having a guiding face for engaging the face of the blank remote from the 20 roller for guiding the blank against the said faces of said roller, said guiding face lying on a line intersecting the periphery of said roller and thereby causing the blank to engage and adhere to the glue applying faces 25 of the roller by the adhesion of the glue throughout a portion of the periphery of the roller, said faces operating to advance the blank therewith, a second roller opposite said first roller and having a plurality of 30 separated glue applying faces out of alinement with said first faces for applying glue between the points of application of the glue by said first named glue applying faces, means adjacent the periphery of the first 35 named roller for disengaging the blank therefrom and for guiding the same onto the said second named roller, feed rollers for advancing the blank past said first named roller, means for supporting a pile 40 of blanks to be fed to the machine, and means for feeding the blanks one by one from the pile to said feed rollers.
6. In a machine for applying glue to individual blanks, in combination, a roller having separated glue applying faces, fixed guiding means having a guiding face for engaging the face of the blank remote from the roller for guiding the blank against the said faces of said roller, said guiding 45 face lying on a line intersecting the periphery of said roller and thereby causing the blank to engage and adhere to the glue applying faces of the roller by the adhesion of the glue throughout a portion of the periphery of the roller, said faces operating to advance the blank therewith, a second roller opposite said first roller and having a plurality of separated glue applying faces out of alinement with said first faces 50 for applying the glue between the points of application of the glue by said first named glue applying faces, means adjacent the periphery of the first named roller for disengaging the blank therefrom and for 55 guiding the same onto the said second
- named roller, feed rollers for advancing the blank past said first named roller, means for supporting a pile of blanks to be fed to the machine, means for feeding the blanks one by one from the pile to said feed rollers, 70 and a conveyer for the glued blanks disposed over said first named roller and separated guide strips projecting into the spaces between the glue applying faces of one of said rollers operating to turn over the 75 blanks and deliver them to said conveyer with the uncoated faces toward the conveyer.
7. In a machine for applying glue to individual blanks, in combination, a pair of spaced rollers each having separated glue applying faces, the faces of one roller being out of alinement with the faces of the other roller, fixed guiding means arranged adjacent said rollers having guiding faces for 80 engaging the side of the blank remote from said rollers on which the side of the blank remote from the rollers slides, said guide faces being disposed on a line intersecting the peripheries of said rollers at said glue 85 applying faces, guide fingers projecting past the glue applying faces of the first roller that receives the blank for engaging the sides of the blank adjacent the rollers, and a plurality of guide fingers disposed 90 between said rollers for taking the blank from the first roller to receive the blank, said fingers projecting across the periphery of the first roller between the glue applying faces thereof and projecting in the 95 other direction toward the other roller and terminating adjacent the glue applying faces of said other roller, all of said fingers co-operating with said guiding means to guide the blanks along a portion of the periphery 100 of the glue applying faces of both of said rollers.
8. In a machine for gluing blanks on one side, in combination, a roller, a second roller spaced therefrom, said rollers each 110 having separated glue applying collars, the collars of one roller being out of alinement with the collars of the other roller, feed rollers for feeding the blanks toward and across said rollers, a plurality of guide fingers projecting and terminating in the 115 spaces between the collars of said first named roller and guiding the blanks onto the collars of the second roller, and means for entirely supporting said guide fingers 120 between said rollers.
9. In a machine for gluing blanks on one side, in combination, a roller having a plurality of separated glue applying faces, a second roller having a plurality of separated glue applying faces, said second named glue applying faces being out of alinement with said first named glue applying faces, a plurality of guide fingers corresponding to each of said glue apply- 130

6

ing faces of said first named roller for engaging the side of the blank remote from the rollers, said fingers having guiding edges disposed on a line intersecting the periphery of the first named roller and terminating adjacent to the glue applying faces thereof, a plurality of guide fingers co-operating with said first named guide fingers disposed adjacent thereto between said 5 glue applying faces of said first named roller, projecting inwardly and terminating beyond the periphery thereof, a second plurality of guide fingers disposed between said rollers having forward extensions disposed between the glue applying faces of said first roller projecting inwardly and terminating beyond the periphery of said first named roller, having extensions projecting toward the said glue applying faces 10 of said second named roller and terminating adjacent thereto, and a plurality of other guide fingers disposed between said

rollers having extensions projecting toward the glue applying faces of said second named roller and having guiding edges on 25 a line intersecting the periphery of said second named roller at said glue applying faces, all of said fingers co-operating to cause the passing blanks to adhere to the glue applying faces of said rollers through 30 the adhesion of the glue on said faces through a portion of the periphery of said rollers and without the application of pressure on the remote side of the blanks at the points where they contact with the glue 35 applying rollers.

In testimony whereof we have hereunto set our hands in presence of two subscribing witnesses.

JAMES D. REIFSNYDER.
HARRY B. SMITH.
